UNITED STATES PATENT OFFICE.

PETER F. MAUER, OF STAPLES, MINNESOTA.

PAPER-BAG CABINET.

SPECIFICATION forming part of Letters Patent No. 602,082, dated April 5, 1898.

Application filed April 30, 1897. Serial No. 634,633. (No model.)

To all whom it may concern:

Be it known that I, PETER F. MAUER, a citizen of the United States, residing at Staples, in the county of Todd and State of Minnesota, have made certain new and useful Improvements in Paper-Bag Cabinets, of which the following is a specification.

This invention relates to cabinets or cases for holding paper bags; and it consists in the construction, combination, and arrangement of parts, as hereinafter shown and described, and specifically pointed out in the claim.

In the drawings, Figure 1 is a front elevation, and Fig. 2 is a plan view, of the cabinet closed. Fig. 3 is a cross-sectional view of the cabinet closed, and Fig. 4 is a cross-sectional view of the cabinet open. Fig. 5 is an enlarged sectional view through one of the compartments, and Fig. 6 is a sectional view on the line X X of Fig. 5.

This cabinet consists of a casing divided into compartments corresponding to the different sizes of paper bags and with a hinged cover, by which access may be had to all the compartments for the purpose of inserting the bags, and each compartment provided with a sliding shelf having a spring connected to keep the sliding shelf normally in its inward position and with a hinged front to each compartment connected to its respective sliding shelf, so that when the front is opened the sliding shelf will be drawn outward and returned inward by the action of the spring.

The paper bags are placed upon the sliding shelves and held by a pin or other fastening, which, while retaining the bags with force sufficient to keep them in place, will yield to the force necessary to pull the required bag from the pile.

In the drawings illustrating my invention the casing is formed with the bottom A', back A², ends A³ A⁴, and hinged top A⁵, the interior being divided into compartments by cross-partitions A⁶, the widths of these compartments being made to correspond to the widths of the various sizes of paper bags. The lengths of the compartments will preferably be equal to the length of the longest bag, but the casing may be formed wider at one end than at the other, corresponding to the progressive lengths of the various sizes of bags.

In the illustration nine of the compartments

are shown, but the number may be increased or decreased and the sizes varied to any desired extent. Each compartment is provided with a front A⁷, hinged at b' to the bottom A' and opening downward, as shown in Fig. 4. Each compartment is provided with a sliding shelf B', arranged to run upon ways d' d², so as to leave a vacant space between the bottom A' and the shelf for a coiled spring e', attached by one end at e² to the bottom A' and at the other end at e³ to the bottom of the shelf, so as to hold the shelf normally in its inward position, as shown in Figs. 3 and 5.

Each of the hinged fronts A⁷ is connected by rods D to the sides of the shelf in the compartments which the front covers, so that as the front is opened downward the shelf will be drawn outward with it, as shown in Fig. 4. When the front A⁷ is turned down to its lowest point, the pivots g' g² at the ends of the rods D and the hinges b' may be so nearly in line with the shelf and its spring that the shelf will be locked in its outward position, as in Fig. 4; but by simply pushing the front upward slightly the spring will draw the shelf inward and close the front by reason of the connecting-rods D.

If it is not desired to lock the front and shelf in their outward position, the front should not be turned down to quite so low a point.

The supply of bags will be placed upon the shelf, as shown at E in Figs. 3 and 4, and held in place by some means which, while retaining the bags with a force sufficient to prevent them from falling from the cabinet or to retain all the bags except the one desired, will permit the desired bag to be readily removed without disturbing the others.

A very satisfactory holding device, which fully meets the above requirements, is shown in the drawings, consisting simply of a pin h, fixed in each of the shelves B' near its inner end and adapted to be passed through the projecting side of the open ends of the bags. By this simple arrangement when a bag is desired the front A⁷, covering the compartment containing the bags of the required size, is opened downward, which draws the shelf and its supply of bags outward, as in Fig. 4, in a convenient position for the salesman, and after the removal of the required bag the

bags are automatically withdrawn into the casing and the front closed, so that they are fully protected from dust or flies and kept in a neat and orderly manner.

5 All the parts will preferably be of sheet metal, but may be wholly of wood or partially of wood and partially of metal, as required.

Having thus described my invention, what I claim as new is—

10 In a paper-bag cabinet, a casing divided into compartments corresponding to the sizes of bags, and with a hinged front to each of said compartments, a sliding shelf in the bottom of each of said compartments upon which

the supply of bags is retained, and supported upon ways by which a cavity is formed beneath each shelf, a spring in each of said cavities connected by its ends to the casing and the shelf, and rods connecting each of said shelves to its respective front, substantially as hereinbefore set forth.

In testimony whereof I have hereunto set my hand in the presence of two subscribing witnesses.

PETER F. MAUER.

In presence of—

JNO. D. MARLIN, Jr.,
CHAS. BACKER.
